UNITED STATES PATENT OFFICE.

JACOB I. SCHAFER, OF NEW YORK, N. Y., ASSIGNOR TO SLOTE & SCHAFER, OF MOUNT VERNON, NEW YORK, A COPARTNERSHIP CONSISTING OF JACOB I. SCHAFER AND REUBEN SLOTE.

DESIGN FOR A BELT SLIDE.

Application filed December 31, 1923. Serial No. 8,203. Term of patent 3½ years.

To all whom it may concern:

Be it known that I, JACOB I. SCHAFER, a citizen of the United States, residing in the city, county, and State of New York, have invented a new, original, and ornamental Design for a Belt Slide, of which the following is a specification, reference being had to the accompanying drawing, forming part thereof.

The figure is a plan view of a design for a belt slide showing my new design.

I claim:

The ornamental design for a belt slide as shown.

JACOB I. SCHAFER.
